UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

TUBULAR-MAGAZINE GUN.

961,412.

Specification of Letters Patent. Patented June 14, 1910.

Application filed December 29, 1909. Serial No. 535,408.

To all whom it may concern:

Be it known that I, THOMAS C. JOHNSON, a citizen of the United States, residing at New Haven, in the county of New Haven 5 and State of Connecticut, have invented a new-and useful Improvement in Tubular-Magazine Guns; and I do hereby declare the following, when taken in connection with the accompanying drawings and the 10 letters of reference marked thereon, to be a full, clear, and exact description of the same, and which said drawings constitute part of this specification, and represent, in—

Figure 1 a broken view in vertical longitudinal section of a gun constructed in accordance with my invention, the pivotal cartridge cut-off being shown in its cut-off position. Fig. 2 a corresponding view showing the cut-off in its retired position. Fig. 20 3 a view in vertical transverse section on the line $a-b$ of Fig. 1. Fig. 4 a detached view in inside elevation of the cut-off. Fig. 5 a 25 detached plan view thereof. Fig. 6 a broken view in inside elevation of the rear end of the action-bar. Fig. 7 a broken view in vertical section on the line $c-d$ of Fig. 1, showing the entrance of the flange 28 of the cut-off 2 into the vertical cut 29 in the forward end of the receiver. Fig. 8 a broken view 30 of the gun in horizontal section on the plane of the lower edge of the action-bar, to show how the cartridge cut-off is mounted and held in place.

My invention relates to an improvement 35 in tubular magazine shot guns, the object being to provide such guns with a simple, compact, durable and reliable cartridge cut-off constructed with particular reference to being positively operated in both directions.

With these ends in view, my invention 40 consists in certain details of construction and combinations of parts as will be herein-after described and pointed out in the claims.

In carrying out my invention as herein shown, I employ a cartridge cut-off 2 in the form of a lever fulcrumed about midway of its length on an outwardly projecting trunnion 3 entering a suitable trunnion-hole, not 45 shown, but located in the inner face of the left hand wall of the gun-frame or receiver 4 which is formed with a crowning solid top 5 and provided in its right hand wall with a lateral ejection-opening 6 and made 50 open at the bottom to provide a feeding

opening 7. The rear end of the cut-off 2 is upturned and forms a lifting-cam 8 adapted to be engaged by the extreme rear end 9 of the action-bar 10 during the rearward movement thereof, the said action-bar 60 being connected at its forward end with a sliding handle 11 which is mounted for sliding movement back and forth upon the tubular magazine 12 which is furnished as usual with a follower 13 and helical fol- 65 lower-spring 14. I may here add that the action-bar 10 and cartridge cut-off 2 are constructed, arranged and timed so that the rear end 9 of the bar 10 engages with the lifting-cam 8 of the cut-off 2 so as to positively rock the same on its trunnion 3 and cause the curved cut-off nose 15 at the forward lower corner of the cut-off to be positively lifted in front of the mouth of the tubular magazine during the expulsion of 75 the rearmost cartridge upon the spoon-like forward end 16 of the pivotal cartridge-carrier 17 so as to be in readiness to prevent the expulsion of the next succeeding cartridge. The nose 15 before mentioned is 80 curved to substantially conform to the curvature of the head of a cartridge and extends inward from left to right from the lower forward corner of the cut-off. At its forward end the cut-off is formed with a 85 depressing-cam 18 which enters a long clearance cut 19 formed in the lower inner edge of the action-bar 10, the rear end of the cut 19 terminating in a cam-surface 20 which, in the forward movement of the action-bar, 90 engages with the cam 18 and positively depresses the forward end of the cut-off 2 and hence the cut-off nose 15 which at this time moves entirely below the lower portion of the mouth of the tubular magazine, and thus 95 permits the rearmost cartridge therein to be expelled therefrom and moved upon the spoon-like forward end 16 of the cartridge-carrier 17 as shown in Fig. 2.

The parts just described are constructed 100 and timed so that the forward end of the cut-off 2 is not depressed until after the compound movement breech-closure 22 has been moved to the limit of its forward excursion and its rear end lifted so as to enter its locking-lug 23 into the locking-notch 24 formed in the inner face of the crowning top 5 of the gun-frame or receiver 4, whereby I avoid any possibility of displacing the breech-closure 22 by the rearmost cartridge as the 110

same is expelled under the power of the fol-
lower-spring 14.

The breech-closure 22 is operated by the
action-bar 10 which for this purpose is pro-
vided with an inwardly projecting lug 25
entering a cam-path, not shown, but formed
in the left hand wall of the breech-closure.
The pivotal carrier 17 swings upon a pivot
26 and is formed at its rear end with an
operating arm 27 the use of which forms no
part of my present invention, having been
fully disclosed in my concurrently pending
application filed November 27, 1909, Serial
No. 530,081.

15 As herein shown I provide for conven-
iently and reliably assembling the cut-off 2
by its provision at its forward end with a
vertically arranged blade-like assembling
flange 28 which enters a vertical cut 29 in
20 the forward end of the receiver, while the
rear end of the cut-off is formed with a re-
taining lug 30 over which a fixed portion 31
of the gun engages, the flange 28 and retain-
ing lug 30 coacting to hold the trunnion 3 in
25 place in its seat. To put the cut-off into the
gun, the flange 28 at its forward end is en-
tered into the vertical cut 29, near the for-
ward end of the receiver. The cut-off is
30 then swung inward upon its forward end,
acting as a fulcrum, for the entrance of its
trunnion 3 into a trunnion-hole provided for
it, but not shown, in the inner face of the
left hand wall of the gun-frame. The
35 guard, of which the part 31 is a part, is now
put in place, whereby the retaining-lug 30,
toward the rear end of the cut-off, is en-
gaged for confining the inner end of the
cut-off against lateral displacement.

The construction just described provides
40 for holding the cut-off in place without the
use of pins or screws, and permits it to be
assembled and dismounted without any tools
and with the utmost readiness.

It will be understood from the foregoing
45 that my improvement provides for the posi-
tive operation in both directions of the cut-
off directly by the action-bar as the same is
moved forward and back in correspondence
with the movement of the action handle.
50 Thus, after the action-bar has operated to
move the breech-closure to the limit of its
forward excursion and lifted its rear end
into its locked position, the action-bar then
coacts with the depressing-cam of the car-
55 tridge cut-off 2 to positively depress the cut-
off nose 15 into its retired position in which
it permits the expulsion of the rearmost
cartridge from the tubular magazine to be
begun. On the other hand, during the rear-
60 ward movement of the action-bar for the
rearward excursion of the breech-closure, the
rear end 9 of the bar engages with the lift-
ing-cam 8 at the rear end of the cut-off, and
positively acts upon the said lifting-cam so
65 as to lift the nose 15 of the cut-off 2 up

against the body of the cartridge being ex-
pelled, and therefore into position to engage
with the head of the next succeeding car-
tridge and prevent the expulsion of any por-
tion thereof from the magazine until the 70
action-bar has again been moved forward so
as to lock the breech-closure in its closed po-
sition directly after which it positively coacts
with the depressing-cam 18 of the cut-off so
as to release what is now the rearmost car- 75
tridge and permit the expulsion thereof to
be begun.

To receive the action-bar 10, the inner face
of the left hand wall of the gun-frame or
receiver 4 is formed with a horizontal groove 80
32 below which is located a recess 33 for
the reception of the cut-off 2, as shown in
Fig. 3 of the drawings.

I claim:—

1. In a tubular magazine gun, the combi-
nation with the gun-frame or receiver there-
of, of a tubular magazine, a sliding handle
mounted thereupon, a breech-closure, an ac-
tion-bar connected at its forward end with
the said handle and at its rear end with the
said breech-closure and moving back and
forth in a groove formed in one of the side
walls of the gun-frame or receiver, and a
pivotal cartridge cut-off located in a recess
formed in the same wall of the gun-frame 95
or receiver as the said groove and situated
below the same, said action-bar directly en-
gaging the said cut-off for positively lifting
the forward end thereof into its cut-off po-
sition. 100

2. In a tubular magazine gun, the combi-
nation with the gun-frame or receiver there-
of, of a tubular magazine, a sliding handle
mounted thereupon, a breech-closure, an ac-
tion-bar connected at its forward end with
the said handle and at its rear end with the
said breech-closure and sliding in a groove
formed in one of the side walls of the said
gun-frame or receiver, and a pivotal car-
tridge cut-off located in a recess formed in
the same wall of the gun-frame or receiver
as the said groove and situated at a point
below the same, the forward end of the
said cut-off being directly engaged by the
said action-bar for positively depressing the
cut-off into its retired position in which the
cartridges are free to be fed out of the tubu- 115.
lar magazine. 110

3. In a tubular magazine, the combination
with the gun-frame or receiver thereof, of
a tubular magazine, a sliding handle mount-
ed thereupon, a breech-closure, an action-bar
connected at its forward end with the said
handle and at its rear end with the said
breech-closure and sliding in a groove
formed in one of the side walls of the said
gun-frame or receiver, and a pivotal car-
tridge cut-off located in a recess formed in
the same wall of the gun-frame or receiver
as the said groove and situated below the 130
120
125
130

same, and the said cut-off having its respective ends directly engaged by the said action-bar for operation thereby, the rearward movement of the bar swinging the cut-off 5 into its cut off position and the forward movement of the bar depressing the cut-off into its retired position.

4. In a magazine gun, the combination with the gun-frame or receiver thereof, of 10 a pivotal cartridge cut-off having a trunnion between its ends and located in a recess formed for it in one of the side walls of the said gun-frame or receiver and having its said ends engaged on its side opposite its 15 said trunnion, by portions of the said frame, whereby the cut off is held in place.

5. In a tubular magazine gun, the combination with the gun-frame or receiver thereof, of 20 a tubular magazine, a sliding handle mounted thereupon, a breech-closure, an action-bar having its forward end connected with the said handle and its rear end with the said breech-closure and sliding in a groove in one of the side walls of the said 25 gun-frame or receiver, and a pivotal cartridge cut-off located in a recess formed in the same wall of the said gun-frame or receiver as the said groove and situated at a point below the same and having its forward end entered into the said clearance cut the rear end of which engages with the said forward end of the cut-off and depresses the same.

In testimony whereof, I have signed this specification in the presence of two subscribing witnesses.

THOMAS C. JOHNSON.

Witnesses:

FRANK A. PAUL,
DANIEL H. VEADER.

flange entering a vertical cut in the said gun-frame or receiver, whereby the forward end of the cut-off is held against lateral displacement.

6. In a tubular magazine gun, the combination with the gun-frame or receiver thereof, of 35 a tubular magazine, a sliding handle mounted thereon, a breech-closure, an action-bar connected at its forward end with the said handle and at its rear end with the said breech-closure, sliding in a groove 40 formed in one of the side walls of the gun-frame or receiver, and having a long clearance cut formed in its inner face; and a pivotal cartridge cut-off located in a recess formed in the same wall of the said gun-frame 45 or receiver as the said groove and situated at a point below the same and having its forward end entered into the said clearance cut the rear end of which engages with the said forward end of the cut-off and depresses the same.
